UNITED STATES PATENT OFFICE.

GEORGE W. DONNING, OF EAST ORANGE, NEW JERSEY, ASSIGNOR TO
HARRY T. AMBROSE, OF ORANGE, NEW JERSEY.

RIBBON MECHANISM FOR TYPE-WRITERS.

No. 826,481.

Specification of Letters Patent.

Patented July 17, 1906.

Application filed June 21, 1901. Serial No. 45,489.

To all whom it may concern:

Be it known that I, GEORGE W. DONNING, a citizen of the United States, residing at East Orange, in the county of Essex and State of New Jersey, have invented certain new and useful Improvements in Ribbon Mechanism for Type-Writers; and I do hereby declare the following to be a full, clear, and exact description of the invention, such as will enable others skilled in the art to which it appertains to make and use the same.

This invention relates to type-writers, and more particularly to ribbon mechanisms therefor.

The object of this invention is to provide improved means for feeding and positioning a ribbon, preferably over a flat platen, and particularly to provide means whereby the ribbon-spools may have a slight movement independent of their supports, as when the ribbon is momentarily drawn out under the impact of a type, and whereby the spools will automatically take up slack after such impact, and also to provide means whereby the spools may be rotated manually independent of the driving mechanism to take up slack in excess of the amount which the spools are capable of taking up automatically.

A further object of the invention is to provide novel means for effecting reversal of the feed of the ribbon.

With these objects in view the invention may be said to consist in the constructions and arrangements described in the following specification and more particularly pointed out in the claims.

In the drawings, Figure 1 is a top plan of the laterally-traveling carriage of a flat-platen type-writer having one embodiment of my invention incorporated therein. Fig. 2 is an elevation of the left end of the carriage. Fig. 3 is a view similar to Fig. 2, some of the parts being now shown in section. Fig. 3' is a view similar to the last, but of the opposite end of the carriage. Fig. 4 is a horizontal section through one of the driving-pinions, showing the means for operatively connecting and disconnecting the pinion with its shaft, the locking-pawl being shown in engagement with its ratchet-wheel. Fig. 5 is a similar view with the pawl out of engagement. Fig. 6 is a longitudinal section

through the pinion. Fig. 7 is an end elevation of the traveling carriage, showing a modified form of my invention in which the step-by-step movement of the ribbon is governed directly by the key-levers. Fig. 8 is a plan view of the parts shown in the preceding figure. Fig. 9 is a rear elevation of the same. Fig. 10 is a fragmentary end elevation illustrating different means for shifting the ribbon-spools longitudinally. Fig. 11 is a similar view showing a slightly further modified construction. Fig. 12 is a plan view of the ribbon-guide. Fig. 13 is a front elevation thereof. Fig. 14 is an end elevation of one of the ribbon-spools. Fig. 15 is a view in end perspective, partly cut away, of the spindle portion of one of the spools, showing the inclosed core and shaft. Fig. 16 is a similar view of the core and shaft with a sectional view of the core, and Fig. 17 is a longitudinal section of one of the ribbon-spools.

In the drawings, A indicates the laterally-traveling carriage of a flat-platen type-writer my invention being particularly applicable to this form of type-writer, and A' is a horizontal rack (which may be the feed-rack) disposed transversely and stationarily above the carriage.

The ribbon-spools a, which may be either single or double, as desired, are mounted toward the lower front portion of the carriage on longitudinal shafts a, so that the spools will feed the ribbon transversely across the printing-point, which in this class of machines is usually at the front of the letter-spacing carriage. Each shaft a (reference now being had more particularly to Figs. 1, 2, 3, 10, and 11) is by means of slot a⁸ and pin a⁹ rotatable with but slidable in a bevel-gear a¹⁰, which is mounted against longitudinal movement in a bearing a¹¹ on the upright side plate A² of the carriage. Gears a¹⁰ are engaged by other bevel-gears a¹², secured to the lower ends of vertical shafts a¹³, it being understood that the gears a¹⁰ occupy reverse positions at the two sides of the carriage, so that the shafts a and spools may be driven in opposite directions.

Shafts a¹³ are provided at their upper ends with loosely-mounted pinions a¹⁴, which mesh with the rack A', and means are provided for operatively connecting and disconnecting the pinions and the shafts. To this end each

pinion is provided with an upward-extending neck portion a^{22x} , encircling the shaft and expanded at its upper end into the platform 22^b . (See Figs. 4, 5, and 6.) Loosely inclosing the shaft and rotatable on said platform is a hollow head a^4 , and rigidly secured to the shaft within this head is a ratchet-wheel a^{25} , which is adapted to be engaged by a pawl a^{26} , pivoted on the platform 22^b . A broken annulus a^{27} is secured to the inner periphery of the head and is so arranged that when the head a^4 is rotated, as indicated in Fig. 5, one end of the broken annulus takes behind the tail of the pawl and forces the latter out of engagement with the ratchet. When the annulus is shifted to the position shown in Fig. 4, a spring a^{27x} , borne on the inside of the annulus, bears against the front of the tail of the pawl and forces said tail out into the broken-away portion of the annulus and the head of the pawl consequently inward into engagement with the ratchet.

Important features of my invention are involved in the manner of mounting the ribbon-spools. Reference being now had more particularly to Figs. 14 and 15, it will be seen that each spool is mounted loosely on a core a^{4x} , which is yieldingly and resiliently connected to shaft a by means of a coiled spring a^{4x} , secured at one end to the shaft and at the other in an aperture a^{4x} in the end of the core. The spool is adapted to be locked to the core by means of a ball or roller a^7 , working in a semicrescent-shaped opening a^5 formed in the inner surface of the spool. It will be understood that Fig. 15 shows the left-hand spool and that in the opposed right-hand spool the opening a^5 is reversed, the result of this arrangement being that when either of the shafts a is rotated to wind up the ribbon on its spool this spool is locked to its core by reason of the ball becoming wedged in the narrow end of the chamber a^5 , while the movement imparted to the opposite spool through the travel of the ribbon causes this spool to be similarly locked. If, however, it is desired to take up a considerable amount of slack in the ribbon or to wind the ribbon on one of the spools for any purpose, this may be accomplished manually by rotating the spool at the time connected with the driving mechanism in the direction of the intermittent ribbon-travel or the other spool in the direction contrary to such travel. During such manipulation it will be readily understood the ball a^7 rolls into the large end of the chamber a^5 , permitting the spool to rotate independently of its support and the driving mechanism.

The coiled spring a^{4x} constitutes means for permitting the yielding of the ribbon under the impact of the type, thereby saving the ribbon from unnecessary wear, and also for automatically taking up the slack in the ribbon after the type-impact, it being obvious

that during all these movements the spools will be locked to their cores and, therefore, in operative connection with the springs.

In order to permit the ribbon-spools to be shifted axially to present new portions of the ribbon, or rather new paths on the ribbon, to the descending type, I mount the shafts a for longitudinal movement in gears a^{10} , as already described. Knobs a^{16} are shown formed on the front of the spools to afford manual means for so shifting the ribbon, and for the purpose of synchronizing the movement axially of the two shafts a at opposite sides of the machine I provide a transverse shaft a^{15} , rigid with which are depending arms a^{14} , having bifurcated ends a^{13} , which straddle the reduced portions a^{12} of the shafts. While the shafts may ordinarily be relied upon to maintain their several longitudinal positions, I may provide means, as indicated in Fig. 2, for retaining the shafts at any one of a number of predetermined points of protraction. As shown, this means consists in a flat spring a^{17} , which is secured to a transverse rod 17^a and bears at its lower end against any one of a number of flattened retaining-faces a^{18} formed on a collar 18^a , rigid with shaft a^{15} . By this arrangement the spools may be retained at different axial positions to disposed different writing-paths over the printing-point or to remove the ribbon entirely from above said printing-point for the purpose of securing visibility. In Fig. 10 is illustrated a modified form of this feature of my invention. Here the shaft a^{16} is provided with a rigidly-attached rearward-extending arm a^{15b} , to which is secured one end of a coiled spring a^{15a} , tensioned so as to protract the shafts a . Pawls a^{21x} , pivoted to the side walls A^2 of the carriage and arranged to engage with reduced regions a^{22x} on the shafts a , retain the shafts at the desired point. In Fig. 11 is illustrated a further modification in which the coil-spring a^{21} encircles the shaft a , bearing at one end against the hub of gear a^{10} and at the other against a collar on the shaft.

It will be readily understood that in the form of my invention illustrated in Figs. 1, 2, 3, 10, and 11 the intermittent longitudinal feed of the ribbon is effected through the engagement of the pinions a^{22} with the rack A^3 , the pinions moving with carriage A in its step-by-step letter-spacing movement along the stationary rack. In Figs. 7, 8, and 9 I have shown a construction in which the intermittent feed of the ribbon is effected directly by the key-levers. Beneath the bank of printing-keys a^{27} is disposed a rod a^{29} , carried by arms a^{30} , which are pivoted intermediate their length and connect at their inner ends by means of pins a^{40} and slots a^{41} with vertical reciprocable rods a^{32} , mounted on the outside of plates A^2 . Beneath the space-key a^{38} is a rod a^{42x} , carried by intermediately-

pivoted arms a^{11} , which are connected with rods a^{22} similarly to the arms a^{33} . It will be evident that depression of either a printing-key or the space-key will elevate the rods a^{33} . These rods carry at their lower ends pivoted pawls a^{33} , which are adapted to engage with opposite sides of ratchet-wheels a^{31} , rigidly secured to shafts a . The pawls are so connected with a transverse rod a^{33x} that when one pawl is in engagement with its ratchet-wheel the other is disengaged, and vice versa. Springs a^{44} may be provided to maintain the pawls in yielding engagement with the ratchets. It will be readily understood that in this form of my invention depression of a key-lever elevates the rods a^{33} and the pawls a^{33} , rotating the engaged ratchet to a slight degree. It will also be apparent that the two ratchet-wheels will rotate their shafts in opposite directions and that therefore to reverse the feed of the ribbon it is only necessary to shift one pawl out of engagement with its ratchet and the other into engagement.

In Figs. 1, 2, 3, 10, 11, 12, and 13 I have illustrated one form of ribbon-guide A^4 , which bridges the space between the spools and is hung therefrom by means of perforated lugs a^1 . At its center, over the printing-point, the guide is cut away, as at a^{44} , and on either side of this opening are provided guiding members a^{44x} . In Figs. 8 and 9 there is shown another form of guide a^{44} , consisting of a narrow slideable plate extending longitudinally at the base of the laterally-traveling carriage. This guide is bifurcated at its front end to carry the ribbon and to leave the printing-point open to the impact of the type end is reciprocated longitudinally simultaneously with the ribbon-spools by means of a depending arm a^{44x} , rigid with shaft a^{13} and pivotally connected at its lower end with the guide.

What is claimed as new is--

1. In a ribbon mechanism, the combination of a rotatable ribbon-carrier, driving mechanism therefor, and a resilient driving connection between and secured to said carrier and driving mechanism, substantially as described.
2. In a ribbon mechanism, the combination of a ribbon-spool, a shaft from which said spool is rotated, and a coil-spring arranged to rotate at one end with the shaft and at the other end with the spool, substantially as described.
3. In a ribbon mechanism, the combination of co-operating ribbon-spools, means for supporting and driving the same, and means for permitting limited yielding of a ribbon carried by said spools, said means being constructed to oppose such yielding and to immediately take up the slack produced thereby, substantially as described.
4. In a ribbon mechanism, the combination of co-operating ribbon-spools, means for supporting said spools, means for imparting an intermittent rotation thereto, and a yielding and resilient connection between each spool and its support arranged to rotate at one end with the shaft and at the other end with the spool, substantially as described.
5. In a ribbon mechanism, the combination of a shaft, means for longitudinally shifting said shaft, means for imparting an intermittent rotation thereto, and a resilient and yielding connection between said spool and shaft arranged to rotate at one end with the shaft and at the other end with the spool, substantially as described.
6. In a ribbon mechanism, the combination of co-operating ribbon-spools, means for intermittently rotating the same to feed the ribbon, and means for permitting slight yielding of the ribbon-spools upon impact of a type, substantially as described.
7. In a ribbon mechanism, the combination with type-bars and actuating mechanism of a ribbon-spool, a driving support therefor, and means for permitting a limited rotation of said spool in a direction opposite to the driving movement at each impact of a type, substantially as described.
8. In a ribbon mechanism, the combination of a ribbon-spool, a driving support therefor, and means for permitting during the period that said support is stationary a limited rotation of said spool in a direction opposite to the driving movement, substantially as described.
9. In a ribbon mechanism, the combination of a winding ribbon-spool, a driving support therefor, and means for permitting a slight backward rotation of said spool under a force exerted in the direction opposite to the driving movement and for automatically reversing such rotation upon removal of the force, substantially as described.
10. In a ribbon mechanism, the combination of an unwinding-spool, a rotatable support therefor, and means for permitting a slight forward rotation of said spool independent of its support and for automatically reversing such rotation upon removal of the force producing the same, substantially as described.
11. In a ribbon mechanism, the combination with a writing mechanism including type-bars, of a ribbon-spool, means whereby the spool is rotated in either direction, and means for permitting limited yielding of the spool distinct from its normal movement to permit slackening of a ribbon carried thereby, said means being operative during rotation of the spool in either direction to automatically take up the slack so produced, substantially as described.
12. In a ribbon mechanism, the combination with a writing mechanism including type-bars, of a ribbon-spool, means whereby the spool is rotated in either direction, and

- means for permitting slight yielding of the spool distinct from its normal movement at each impact of a type, whereby slackening of a ribbon carried by the spool is permitted, said means operating automatically upon the return stroke of the type to compensate for such yielding movement, substantially as described.
13. In a ribbon mechanism, the combination with a writing mechanism including type-bars, of cooperating ribbon-spools, means for rotating and changing the rotation of said spools for feeding and changing the feed respectively of a ribbon carried by the spools, and means for permitting slight yielding of both spools distinct from their normal movement at each movement of a type to print, whereby slackening of a ribbon carried by the spools is permitted, said means acting automatically upon the return stroke of the type-bar to compensate for such yielding movement of the spools, substantially as described.
14. In a ribbon mechanism, the combination of a ribbon-spool, a member upon which said spool is mounted, driving mechanism for intermittently rotating said member to effect feeding of the ribbon, means for locking the spool against rotation upon said member in a direction opposite to driving and for permitting such relative rotation in the opposite direction, and independent means for permitting slight rotation of the spool in a direction opposite to driving independent of the driving mechanism, substantially as described.
15. In a ribbon mechanism, the combination of a ribbon-spool, a member upon which said spool is mounted, driving mechanism, for intermittently rotating said member to effect feeding of the ribbon, means for locking the spool against rotation upon said member in a direction opposite to driving and for permitting such relative rotation in the opposite direction, and independent means for permitting a slight rotation of said spool under a force exerted in the direction opposite to the driving movement and for automatically reversing such rotation upon removal of the force, substantially as described.
16. In a ribbon mechanism, the combination with a rack, a pinion meshing with the rack, a shaft loosely encircled by said pinion, and a ribbon-spool driven from said shaft; of a ratchet-wheel secured to said shaft, a pawl pivoted upon the pinion, and a head rotatable in one direction to engage the pawl with the ratchet and in the opposite direction to disengage it therefrom, substantially as described.
17. In a ribbon mechanism, the combination with a rack, a pinion meshing with the
- rack, a shaft loosely encircled by said pinion, and a ribbon-spool driven from said shaft; of a ratchet-wheel secured to said shaft, a pawl pivoted upon the pinion, and a hollow rotatable head housing said pawl and ratchet and provided with means for engaging and disengaging the pawl with the ratchet, substantially as described.
18. In a ribbon mechanism, the combination with a rack, a pinion meshing with the rack, a shaft loosely encircled by said pinion, and a ribbon-spool driven from said shaft; of a ratchet-wheel secured to said shaft, a pawl pivoted upon the pinion, a hollow rotatable head, a broken annulus carried by said head, and a spring also carried thereby, the spring being arranged to engage with the pawl to hold it in engagement with the ratchet while the pawl is received in the cut-away portion of the annulus and the annulus being arranged to force the pawl out of engagement with the ratchet when the spring is moved out of engagement with the pawl, substantially as described.
19. In a ribbon mechanism, the combination with opposed ribbon-spools rotatable to effect ribbon-feed and shiftable axially to carry the ribbon widthwise, of spool-shifting arms pivoted and connected to insure simultaneous movement thereof, and a flat spring member frictionally associated with said arms to retain them in a plurality of positions.
20. In a ribbon mechanism, the combination with opposed ribbon-spools rotatable to effect ribbon-feed and shiftable axially to carry the ribbon widthwise, of pivoted spool-shifting arms, a connecting pivot-rod rigid with said arms, and a flat spring member bearing against said pivot-rod to retain the parts in a plurality of shifted positions.
21. In a ribbon mechanism, the combination with opposed spools rotatable to effect feeding of the ribbon and shiftable axially to carry the ribbon widthwise, of spool-shifting arms, a connecting pivot member rigid with said arms and provided with a plurality of retaining-faces, and a spring member arranged to engage one or other of said faces whereby different longitudinal writing-paths on the ribbon may be positioned over the printing-point or the ribbon entirely removed from above the said printing-point to secure visibility.

In testimony whereof I affix my signature in the presence of two subscribing witnesses:

GEORGE W. DONNING.

Witnesses:
